UNITED STATES PATENT OFFICE.

WILLIAM C. KENNEY, OF CRANSTON, RHODE ISLAND, ASSIGNOR TO KENNEY MANUFACTURING COMPANY, A CORPORATION OF RHODE ISLAND.

DESIGN FOR A CURTAIN ROD.

Application filed November 28, 1924. Serial No. 11,513. Term of patent 14 years.

To all whom it may concern:

Be it known that I, WILLIAM C. KENNEY, a citizen of the United States, residing at Cranston, in the county of Providence and State of Rhode Island, have invented a certain new, original, and ornamental Design for a Curtain Rod, of which the following is a specification.

In the accompanying drawings which form a part of this specification the figure is a perspective view of a curtain rod embodying my new design.

A feature of the design consists in the appearance of the superficial ornamentation of the rod.

I claim:

The ornamental design for a curtain rod, as shown.

WILLIAM C. KENNEY.
